TRANSFERRING DEVICE

Paul Schönfeld, Chemnitz, Germany

Application July 8, 1932, Serial No. 621,449,
and in Germany August 6, 1931

3 Claims. (Cl. 66—148)

This invention relates to a transferring device. In order to connect knit goods with goods of a different kind or gauge it is customary to turn over the portion to be transferred to a knitting frame or machine on the edge where it is to be picked up so as to cause the needles of the frame or machine to penetrate twice the transferred edge of the portion. Transferring itself may be preparatorily carried out by means of a transferring device of known type, such as is used in connection with every cotton hosiery machine, so that all that is necessary is to run the picked up portion on to the needles of a knitting frame or machine by means of a transfer bar. However, this method is quite wearisome and difficult, since it is left more or less to the skill of the operator to prevent that in some spots more or fewer courses are caught than elsewhere.

To overcome these drawbacks it has been proposed to arrange the portion of the goods to be transferred on the firm edge of a holding device provided on this edge with uniformly spaced depressions, so that the goods depend from this edge on both sides and may be hung on or otherwise attached to the edge by means of an ordinary hanging-in or transfer bar which is inserted in the goods through the depressions of the fixed edge. The device for carrying out this method consists preferably of a buckled needle bar or corrugated plate in connection with an ordinary hanging-in or transfer bar. The application of this method requires therefore a special device, which should be avoided.

This can be done according to the invention, by rendering the known transferring devices with which every knitting frame or machine is equipped suitable for preparing the transfer of a goods section with turned over edge. For this purpose the needle bar of a transferring device of known type is provided, directly behind the needle points, with a holding means up to which the goods run on the needles may be drawn back and then turned over the needle heads, so that the needles will pierce the goods a second time when they are drawn again towards the needle bar. In this way the small roll produced above the transfer line by the turning over of the portion of the goods concerned will be perfectly uniform, and all difficulties are thus eliminated. The holding means may be formed by needles provided with hooks and filled up at their heads for this purpose or a wire corresponding to the width of the transferring device may be inserted in the hooked needles.

It has been proposed already to employ for the

transfer of a portion of goods with turned over edge the needle bar of a cotton frame, which is fitted with barbed needles, but since the hooked needles of a cotton frame do not possess holding means, the roll above them will become so small that it will hardly be possible to carry out this process on an ordinary transferring device, as the goods can be taken off from the device by means of a regular transfer bar under great difficulties only and scarcely be transmitted to a knitting machine.

Two embodiments of the invention are illustrated in the accompanying drawing, in which Figures 1 to 5 show how the transferring process is carried out, the needle bar of one transferring device being disclosed to simplify matters.

In Figs. 1, 2, 3 and 4 the transferring process on the needle bar of one of the usual transferring devices is shown up to the point of transmitting the goods to the transfer bar proper, the holding means, which limits the drawing back of the transferred portion for the purpose of turning it over, being formed merely by needles fitted with small hooks which are filled up at the heads.

Fig. 5 shows how the holding means is formed by a wire corresponding to the width of the device and held in position by small hooks which may, for instance, form part of hooked needles. The needle bar 1 of the transferring device comprises, besides the usual pointed needles 2, at certain spots and preferably at a uniform distance from one another the needles 3 which are fitted with small hooks filled up, at the heads, approximately to an extent corresponding to the width x .

To transfer a portion of goods with a turned over edge the portion 4 is first run on the needles or pins 2 and 3 of the needle bar 1, as shown in Fig. 1, whereupon, as indicated in Fig. 2, the entire portion 4 is drawn back again towards the points of the needles without turning over the top part, the filled up heads of the needles 3 limiting this withdrawal of the part 4 to the width x which corresponds to the filled up portion of the heads. The portion 4 is now pierced by all the needles 2 and 3. Then the top strip 5 of the portion 4 is turned over, as indicated in Fig. 3, so as to be on a plane parallel to that of the portion 4, and when the entire portion 4, as shown in Fig. 4, is drawn back again towards the needle bar 1, the points of the needles 2 and 3 will pierce the portion 4 on the strip 5 a second time.

The small roll formed by doubling up and

positioned above the transfer line will be perfectly uniform and by the holding means, which, in this instance, is formed by the filled up heads of the hooked needles 3, dimensioned so that the transferred portion 4 may be readily taken off in the usual way by means of the transfer bar 6 of known type, as indicated in Fig. 4.

Fig. 5 shows how the device may be altered by fitting the needle bar 1 of the transferring device wholly or partly with ordinary needles 7 possessing a hook but having their heads not filled up. The holding means in this case is simply formed by a wire 8 corresponding to the width of the device and inserted in the hooks of the needles 7. When the portion of goods 4 is run on, the wire 8 having approximately the width x of the filled up needle heads of the embodiment described above is inserted in the hooks of the needles 7 whereupon the top 5 of the portion 4 may, after the latter has been drawn back, be turned down over the wire 8.

When the transferring operation is finished the wire 8 may be withdrawn laterally.

It is immaterial whether the needle bar 1 of the transferring device is fitted wholly or partly with needles having such a small hook.

I claim:—

1. A device for transferring knitted goods from one knitting frame or machine to another, comprising a bar having a plurality of pins of which a number are provided with hooks on the ends of the pins which are filled up a substantial distance back from the point of the hook to prevent the goods from slipping off the pins.

2. A device according to claim 1, in which the filled up portions of the hooks of the number of the pins form integral parts of the hooks.

3. A device according to claim 1, in which the filled up portions of the hooks of the number of pins comprises a removable wire provided in the hooks.
